UNITED STATES PATENT OFFICE

CHARLES M. WARDAN, OF KIRKWOOD, MISSOURI

SHIRT CONSTRUCTION

Application filed May 16, 1928. Serial No. 278,180.

This invention relates to improvements in shirts, and more particularly to a reinforced sleeve specially adapted for work shirts and the like.

An object of the invention is to provide a construction in which the sleeve is reinforced at the point of greatest wear by a sewed in reinforcement member constructed as a part of the shirt sleeve which will give to the finished sleeve a neat appearance, and which will provide a durability to resist surface wear and strain, and will also reinforce the upper placket opening of the sleeve.

Another object of the invention is to provide a sewed in reinforcement member for the back of a sleeve and extending outwardly from the elbow section toward the wrist, said reinforcement member being constructed as a part of the shirt by turning in the edge of said reinforcement in the felling seam, thereby providing a neat appearance, cheapening the cost of manufacture and improving the durability of the shirt sleeve.

Other objects of the invention will be apparent from the following detailed description thereof, taken in connection with the accompanying drawing in which

Fig. 1 is an elevation of the back of the lower portion of the sleeve.

Fig. 2 is a sectional view on the line 2—2 of Fig. 1.

Fig. 3 is a reverse view of the sleeve further illustrating the construction.

The general construction of the sleeve is conventional, the sleeve body being made up of longitudinal sections 1 and 2 to provide the tapering shape from the shoulder to the cuff 3. The felling seam 4 extends along the lower edge of the sleeve and serves to join one edge of the longitudinal section 1 to the longitudinal section 2 and an intermediate seam 5 serves to join the opposite edge of the section 1 with the section 2.

The lower portion of the sleeve is formed with an open placket around which above the cuff portion is a continuous facing strip having a section 6 stitched to the edge of the rear section of the placket and being turned back or folded at the line 7 and having an extended portion 8 which turns inwardly from the

rear edge of the front portion of the placket. The placket constructed in this manner forms a flat closure for the sleeve.

It is with this general construction of the shirt sleeve that the reinforcement constituting the novelty of the present invention is associated. A sleeve, particularly in work shirts, having a single thickness of cloth, has a tendency to pull out at the elbows from strain and from frictional wear. Furthermore, in shirts of this character, the sleeves of which are frequently rolled, there is a tendency to pull out or to rip or tear at the upper end of a placket opening. Several expediences have been adopted in an effort to prevent the frictional wear, such as sewed on patches not formed as a part of the sleeve, but these expediences have been unsatisfactory because they do not give to the shirt sleeve a neat finished appearance. Furthermore, such sewed on patches not formed as a part of the sleeve do not take account of nor do they prevent the ripping or tearing out of the placket opening of the shirt.

The present construction includes a substantially rectangular reinforcement member 9 which is applied to the sleeve portion at the elbow section thereof and is constructed as a part of the shirt by forming the vertical edge 10 as an inturned portion of the felling seam 4, the connection between the edge 10 of the reinforcement member and the sleeve proper being performed at the same time the felling seam is sewed. The reinforcement member is so positioned on the sleeve that the lower edge 11 thereof traverses the sleeve at a point below the folded section 7 of the placket, the attaching stitching 12 forming a reinforcement for the upper end of the placket, it being clear that the stitching 12 that is utilized for connecting the lower edge 11 of the reinforcement member 9 with the sleeve also serves as a reinforcing line of stitching across the placket. Thus, with the reinforcement member 9 stitched across the placket opening, the placket opening is so reinforced as to prevent it from tearing out, even with unusual wear. The vertical edge 13 of the reinforcement member as well as the upper edge 14 of the reinforcement member

are directly stitched to the shirt sleeve body by a continuation of the line of stitching 12, (Fig. 1).

From the foregoing description of the construction it will be apparent that it fully accomplishes the purposes of the invention. It will also be understood that the invention may be modified in various particulars without departing from the nature and principle thereof.

10 What I claim and desire to secure by Letters Patent is:—

1. A sleeve construction comprising two longitudinal sections, and a felling seam and 15 an intermediate seam securing together the adjacent edges of said sections and forming a sleeve having a placket opening extending upwardly from the lower end of the sleeve beyond said intermediate seam from said felling seam, in combination with a reinforcement member on the outer side of the sleeve and having its lower edge above said placket opening, and having one of its vertical edges attached to the sleeve by said felling seam, 20 said reinforcement member extending across one of said sections and across the adjacent portion of the other section at the upper end of said placket opening and extending beyond said placket opening from said intermediate seam and having its edges sewed to said sections of said sleeve.

2. A shirt sleeve construction comprising two longitudinal sections, and seams uniting said sections along their longitudinal edges 25 and one of said sections having a placket opening extending upwardly from its lower end and the other section being without a placket opening, in combination with a reinforcement member on the outer side of the 30 sleeve and having its lower edge above the placket opening and having one of its vertical edges attached to the sleeve by one of said seams, said reinforcement member extending across said section which is without a placket 35 opening and across the adjacent portion of said section having said placket opening and extending beyond said placket opening from said other seam and having its edges sewed to said sections of said sleeve above said placket 40 opening.

3. A sleeve construction comprising two longitudinal sections sewed together by seams along their longitudinal marginal portions and one of said sections having a placket 45 opening at its lower end between said seams, in combination with a reinforcement member on the outer side of the sleeve and having its lower edge above said placket opening and having one of its vertical edges attached to 50 the sleeve by the seam that is at the opposite side of the section other than the section in which said placket opening is formed, said reinforcement member extending across said last named section and also across the adjacent portion of the section in which the

placket opening is formed and extending beyond said placket opening and having its edges sewed to both of said sections of said sleeve.
